Letters Patent No. 2495 Taken Oct. 23, 1866

Design for a Floor Oil Cloth Pattern

The schedule referred to in these Letters Patent, and making part of the same.

To all whom it may concern:

Be it known that I, Charles J. Meyer of Bergen County of Hudson and State of New Jersey have invented or produced a new, original and ornamental Design or Pattern for Floor Oil Cloths, carpets and other fabrics; and do hereby declare that the accompanying drawing marked and designated as Design No. 4, fully represents said design, and is sufficient without further aid to enable any person skilled in the art to which it appertains to repeat it for practical use; otherwise and the arrangement of them may, in the use of this design, be varied to suit the views or fancy of the user or manufacturer of articles ornamented by said design.

This design may be of any size or color in kind or number or in any contrast or blending of colors, or of light and shades.

I claim as new and desire to secure by Letters Patent of the United States, the Design for Floor Oil cloths, carpets &c. as shown and described.

Witnessed,

H. P. Pinney
